UNITED STATES PATENT OFFICE.

JOHN BIRKENHEAD, OF MANSFIELD, MASSACHUSETTS.

SPINNING-FRAME SPINDLE AND ITS BOLSTER.

SPECIFICATION forming part of Letters Patent No. 295,899, dated April 1, 1884.

Application filed May 15, 1883. (No model.)

To all whom it may concern:

Be it known that I, JOHN BIRKENHEAD, of Mansfield, in the county of Bristol, of the Commonwealth of Massachusetts, have invented a new and useful Improvement in Spinning-Frame Spindles and their Bolsters; and I do hereby declare the same to be described in the following specification and represented in the accompanying drawings, of which—

10 Figure 1 is a front elevation, and Fig. 2 a vertical and transverse section, of a spindle, a bolster-rail, and bolster provided with my invention, the nature of which is duly set forth in the claims hereinafter presented; also, a bobbin as applied to the spindle. Fig. 3 is a vertical section of a bolster provided with stationary instead of removable bearings. Such figure shows the spiral groove in the bore of such bolster. The groove is also represented 20 in Fig. 2, wherein it appears as in the bore of the bolster and in that of the removable bearings thereof. Fig. 4 is a horizontal section of the bolster and its upper removable bearing-sleeve on the line $x x$, Fig. 2.

25 The bolster for the spindle extends up through and both above and below its sustaining-rail, and projects within an oil cup or reservoir fixed to the spindle at its foot, and combined or being in one piece with the whirl. 30 In the whirl is a mouth or passage leading from the top of the said whirl into the oil cup or reservoir below the whirl. The whirl and oil-cup are concentric with the spindle and the part of the bolster extending down within them. The bore of the bolster and the spindle-bearings within said bolsters are grooved 35 spirally from the foot to the top of the bolster in such manner that while the spindle may be in revolution for spinning the yarn oil shall

40 be caused to flow from the oil-cup upward through the bolster and the spindle-bearings to the top of the bolster. The spindle at its foot does not rest and turn in any step, but at the top of the bolster such spindle is provided 45 with a collar flange or bearing to rest directly on the said top, or upon that of a removable metallic sleeve or upper spindle-bearing inserted in the bolster. Furthermore, the said spindle collar flange or bearing, by which

the spindle is kept from dropping downward 50 in the bolster, is formed with an annular lip to extend from it into an annular groove or chamber made in the bolster at its top. This annular groove is to intercept any oil that may escape between the top of the bolster and the 55 spindle collar or flange resting thereon. The annular lip serves to deflect such oil into the said groove or chamber, and to keep it from being discharged over the chamber and bolster by centrifugal force while the spindle may 60 be in revolution. At the upper part of the oil-cup, and within the whirl, there is an enlargement or an annular groove or chamber provided at top with an annular lip or flange, which extends down within such enlargement 65 or groove, and with it serves to prevent oil, while the spindle and cup and whirl may be in rapid revolution, from being thrown out of the cup.

In the drawings, A denotes the spindle; B, 70 the bolster, and C the bolster-supporting rail, the bolster being held in the rail by a set-screw or other proper means. D is the oil cup or reservoir, and E the whirl. F is the spindle-sustaining flange collar, or uppermost bearing, 75 it resting on the top of the bolster or that of a brass bearing-sleeve, G, surrounding the spindle and arranged within the bolster concentrically. Another such sleeve is shown at H as inserted in the bolster at its lower part. 80 Each sleeve may be encompassed with yielding packing or cloth sleeve I. The bolster, however, can be constructed without the removable sleeves G and H, but with stationary spindle-bearings, as represented at G and H 85 in Fig. 3.

The enlargement or annular chamber in the whirl and oil-cup is shown in Fig. 2 at a, the mouth or passage at a', and its annular lip or flange at b. The spiral groove in the bolster and the spindle-bearings of its bore is represented at c. Instead of forming such groove in the bolster and its spindle-bearing, it may be made in and around the spindle itself; but it is better to have it in the bolster and the said 95 bearings.

The annular chamber in the top of the bolster is shown at d, the lip projecting down into

it from the flange collar, or uppermost bearing, F, being represented at e.

Oil for supplying the cup at the foot of the spindle is to be poured into the mouth formed 5 in the whirl.

When the spindle may be in rapid revolution by a band applied to its whirl, the oil will be forced or drawn from the oil-cup upward through the bolster to the bearing-flange 10 of the spindle, and will lubricate the bearing-surfaces of the spindle and bolster.

I claim—

1. The bolster having the spindle collar flange or bearing and the surrounding oil-intercepting chamber in its upper part, as set forth, 15 in combination with the spindle extended down through the bolster, and provided not only with the flange or collar to rest on and encompass the aforesaid bearing, but with a combined whirl and oil-cup adapted to the 20 said spindle at its lower part, having a mouth or passage opening into the said cup, and arranged with the bolster, as represented, the bore of the bolster having a spiral groove, as 25 and for the purpose explained.

2. The bolster provided with the separate bearing-sleeves arranged in it as represented, in combination with the spindle extending through and above such sleeves, and having not only the flange or collar to rest and revolve on the top of the upper of such sleeves, but the combined whirl and oil-cup adapted to it, the said spindle having a mouth or passage opening into the said cup, and arranged with the bolster, all being substantially as set forth. 30 35

3. The bolster provided with the separate bearing-sleeves and with their yielding packings or surrounding sleeves, in combination with the spindle extending through and above the said bearing-sleeves, and having not only the flange or collar to rest and revolve on the top of the upper of such bearing-sleeves, but the combined whirl and oil-cup adapted to it 40 the said spindle, and arranged with the bolster, all being substantially as represented. 45

JOHN BIRKENHEAD.
